UNITED STATES PATENT OFFICE.

GEORGE W. HANNER, OF LORDSBURG, NEW MEXICO.

FISHPLATE.

Original application filed August 12, 1920, Serial No. 403,081. Patent No. 1,403,027, dated January 10, 1923. Divided and this application filed April 7, 1921. Serial No. 459,423.

To all whom it may concern:

Be it known that I, GEORGE W. HANNER, citizen of the United States, residing at Lordsburg, in the county of Hidalgo and 5 State of New Mexico, have invented certain new and useful Improvements in Fishplates, of which the following is a specification.

This invention relates to an improved fish plate for connecting the meeting ends of rail- 10 way rails, being a division of my application for railway tie and rail fastening, filed Au- gust 12, 1920, Serial No. 403,081, Patent 1,403,027, Jan. 10, 1922.

Among other objects, the invention seeks 15 to provide a fish plate which may be readily produced and which will be adapted to co- act with the track ties for holding the plate against longitudinal movement so that ex- pansion and contraction of the rails will be 20 equalized therebetween.

A further object of the invention is to provide a fish plate which, while being par- ticularly adapted for use in connection with the structure shown in my prior application 25 referred to, will also be adapted for gen- eral use.

And the invention has as a still further object to provide a fish plate which will co- act with the track ties at the joints between 30 the rails, to prevent creeping of the ties.

Other and incidental objects will appear hereinafter.

In the drawing:

Figure 1 is a fragmentary plan view show- 35 ing a section of track, as illustrated in my prior application previously referred to, and illustrating a pair of the fish plates applied,

Figure 2 is a fragmentary side elevation showing the manner in which the lugs of the 40 plate are disposed to coact with the side walls of the track ties, and

Figure 3 is a perspective view showing one of the fish plates in detail.

Referring now more particularly to the 45 drawing, I have illustrated my improved fish plate in connection with a section of railway track embodying ties and rail fasteners as exemplified in my pending application previously identified and, for con- 50 venience, I shall first generally describe the tie and fastener of the parent application. The tie is preferably formed of metal and, as will be observed, is constructed with a bottom wall 10 having spaced parallel side 55 walls 11 rising therefrom. Extending be-

tween said side walls are suitable chair plates upon which rest the rails as conven- tionally illustrated at 12 and formed on the side walls are flanges 13 engaging over the base flanges of the rails at the outer sides 60 thereof. Extending between the side walls in spaced parallel relation to the flanges 13 are stirrups or loops 14 and extending through these loops are clamps 15 cooperat- ing at their inner ends with an adjusting 65 bolt 16 rising from the bottom wall 10 of the tie, a shoe 17 fitting over the inner end por- tions of the clamps. The clamps serve to rigidly bind the rails upon the ties.

Coming now more particularly to the sub- 70 ject of the present invention, I employ, at the meeting ends of the rails, companion fish plates 18. As shown in detail in Figure 3, these plates are provided with spaced openings for receiving the usual bolts con- 75 necting the rails at their ends and formed on the plates at their lower margins are medial laterally directed stop lugs 19. The lugs 19 are preferably integral with the plate bodies, being bent to extend at sub- 80 stantially right angles thereto and, as will be noted, the plate bodies are slit upwardly from their lower edges at the side edges of the lugs so that the lugs may be turned lat- 85 erally. As best shown in Figure 2, the stop lugs 19 fit snugly between the confronting side walls of adjacent ties. At their ends, the fish plates carry, at their lower margins, laterally directed stop lugs 20 alining with 90 the lugs 19, the lugs 20 being also preferably formed integral upon the plate bodies. As in the instance of the lugs 19, the plate bodies are slit upwardly from their lower edges, at the inner side edges of the lugs 20, so that these lugs may be readily turned 95 laterally, the lugs 20, however, being of considerably less width than the lugs 19.

The lugs 20 are, as also best shown in Figure 2, disposed to confront the remote side walls of the ties at the joint between 100 the rails. The lugs 19 and 20 will, there- fore, cooperate with the side walls of said ties for holding the fish plates against longi- 105 tudinal movement so that any expansion or contraction occurring in the rails will be 110 equalized therebetween. Furthermore, the lugs 19 will act to prevent the ties from moving toward each other while the lugs 20 will serve to prevent the ties from spreading so that creeping of the ties supporting the 110

rail joint will also be prevented. I accordingly provide a fish plate of highly efficient design and, as will now be seen, a fish plate which, while being particularly adapted for use in connection with a tie of the character illustrated, may also be employed in connection with ordinary track ties now in common use.

Having thus described the invention, what is claimed as new is:

As a new article of manufacture, a fish

plate including a flat body provided at its lower edge with lateral outwardly bent stop lugs comprising terminal lugs and a third elongated medially disposed lug, the lower margin of the plate being unobstructed between said lugs and being slit upwardly at the inner ends of the lugs to permit lateral bending thereof.

In testimony whereof I affix my signature. 20

GEORGE W. HANNER. [L. S.]
